UNITED STATES PATENT OFFICE

JOSEPH SERTELL AND WILLIAM F. RYAN, OF INDIANAPOLIS, INDIANA.

SPIKE.

1,112,849.

Specification of Letters Patent.

Patented Oct. 6, 1914.

Application filed October 27, 1913. Serial No. 797,563.

To all whom it may concern:

Be it known that we, JOSEPH SERTELL and WILLIAM F. RYAN, citizens of the United States, and residents of Indianapolis, county 5 of Marion, and State of Indiana, have invented a certain new and useful Spike; and we do hereby declare that the following is a full, clear, and exact description thereof, reference being had to the accompanying 10 drawings, in which like letters refer to like parts.

The object of this invention is to improve the construction of a split spike, nail, brad and the like in order that the legs thereof 15 will spread and twist in various ways and thereby come into binding engagement with a much larger portion of the timber into which it is driven than is the case with the ordinary split spike.

The novel feature of the invention consists 20 in providing the end of each spike leg with oppositely curved double or beveled surfaces whereby when the spike is driven, the legs will not only spread from each other in two 25 directions, but they will twist also. Along with the foregoing is the provision of at least one of the legs with a bevel which will tend to prevent the head of the spike from turning very much.

The withdrawal of spikes from cross ties 30 and railways is one of the common causes of railway accidents. The constant jarring of the track by the train gradually elevates and withdraws the spikes without any great resistance of the timber in the cross tie. With 35 spikes of the kind herein set forth such result cannot follow. The spikes cannot be withdrawn and the rails will always be held secure upon the ties.

The nature of the invention will be understood from the accompanying drawings and the following description and claims.

In the drawings, Figure 1 is an elevation of said spike. Fig. 2 is a perspective view 45 of the same after it has been driven. Fig. 3 is an elevation of the spike viewing it from one side. Fig. 4 is a section through a cross tie and railway rail and showing the spike in place in the cross tie, one leg of the spike being shown by dotted lines. Fig. 5 is a bottom view of the spike. Figs. 6 and 7 are sections on the lines 6-6 and 7-7, respectively, of Fig. 2. Fig. 8 is an enlarged section on the line 8-8 of Fig. 4. Fig. 9 is a bottom view like Fig. 5 of a modified form.

In Fig. 4 there is shown a railway rail 10

and cross tie 11 with a split spike therein. The spike has a round head 12 because as the spike is being driven the twisting movement of the legs cause the spike to turn 60 somewhat and the round head will always engage the flange of the railway rail regardless of the amount of twisting of the spike. The spike is split for almost its entire length so as to provide two parallel legs 13 and 14 65 and each leg has near its lower end lateral shoulders 15 which serve as barbs to oppose the withdrawal of the spikes.

The end of each leg has an outside straight face 20. The leg 13 has a straight face 21 70 on one side and the other leg has an upper straight surface 22 diagonally opposite the surface 21 on the other leg, but below the straight surface 22 the leg 14 is beveled at 23 and on the same side as the surface 22. 75 The inner surfaces of both spikes are beveled two ways, vertically and transversely or curved, to make the beveled surfaces 25, but the surfaces 25 on the two legs are beveled reversely to each other.

In the modified form in Fig. 9, there is an inner beveled surface 35 and a lateral beveled surface 36, said two beveled surfaces corresponding with the beveled surfaces 25 in the form heretofore described. Therefore, 85 while the spike is being driven, if it be of the form shown in Fig. 9, the two lateral curved beveled surfaces 36 will cause the legs to spread longitudinally of the timber, as shown in Fig. 8, and the two inner beveled 90 surfaces 35 will at the same time cause the legs to spread transversely of the timber. These two results will also follow from the compound or curved beveled surfaces 25 in the form shown in Fig. 1, with the additional result, however, which is caused by the curved surfaces, namely, the legs will be twisted while being driven, as shown in Fig. 8. In the form shown in Fig. 9, the legs are 95 not twisted, but appear as shown in Fig. 4. 100

The function of the bevel 23 is to prevent the head of the spike from twisting to any great extent. It causes one leg of the spike, as shown in Fig. 4, on entering the wood, to curve or spread longitudinally of the timber 105 less than the other leg, and tends to reduce the turning movement of the head or body of the spike.

The invention is:

1. A split spike with the legs thereof rectangular in cross section and with the ends of each leg widened to form shoulders there

on, the shouldered ends of the legs being beveled both longitudinally and transversely substantially as set forth to a single point at the extreme end of each leg, the points of the 5 two legs being substantially diagonally opposite each other so that the legs will both spread and twist while being driven.

2. A split spike with the ends thereof provided with inner surfaces beveled both longitudinally and transversely so as to cause 10 the legs to spread from each other and simultaneously twist, the end of one of said

legs having an additional bevel for reducing the spreading movement of one of said legs to reduce the twisting movement of the head 15 of the spike while the spike is being driven.

In witness whereof, we have hereunto affixed our signatures in the presence of the witnesses herein named.

JOSEPH SERTELL.
WILLIAM F. RYAN.
